STEERING COLUMN LOCK SWITCH

William C. Edwards, Anderson, Ind., assignor to
 General Motors Corporation, Detroit, Mich.,
 a corporation of Delaware

Application May 24, 1935, Serial No. 23,172

7 Claims. (Cl. 200—55)

This invention relates to locking means for automotive vehicles and more specifically to a unitary locking structure which performs the dual function of locking the steering column against rotation and also locks the ignition circuit.

It is an object of my invention to provide a simple, economical lock having the above dual functions.

10 It is a further object to provide a certain sequence of operation of the parts for purposes of safety.

15 For a better understanding of the nature and objects of this invention, reference is made to the following specification wherein there are described the embodiments of my invention which are illustrated in the accompanying drawings, in which,

20 Fig. 1 is a side elevation of a steering post and wheel with the structure of my invention in its usual position.

Fig. 2 is a sectional view taken on the line 2—2 of Fig. 1.

25 Fig. 3 is an enlarged sectional view taken on the line 3—3 of Fig. 2 showing a diagrammatic ignition circuit connected thereto.

Fig. 4 is a sectional view taken on the line 4—4 of Fig. 3.

30 Fig. 5 is a perspective view showing the movable switch base with contacts.

A steering wheel 2 is rotatably supported on the upper end of the steering column, generally designated at 4, surrounding which is an angular casting 6 having one leg 8 projecting forwardly 35 and upwardly therefrom, the upper end of which is spread out and forms two flat ears 10, the upper surfaces of which have a series of teeth or serrations 12 which teeth engage with the similar serrations 14 on the lower face of an 40 angular bracket 16 secured to the rear face of the instrument panel 18. Bolts 20 extend through elongated openings 22 of the ears and through the arm of the angular bracket 16 to secure the two together.

45 In the main body of the casting 6 is drilled a transverse opening 24 through which the outer casing 26 of the steering column passes. A slot 28 is cut in the casting from the outer surface to the transverse opening 24 to allow the casting to be clamped upon the outer casing 26. A bore 30 is cut at right angles to the slot 28 and a bolt 32 is threaded therein whose action upon tightening the same is to tend to close the slot 28 and clamp the casting upon the steering column. A second leg 34 of the casting lies in

approximately the same plane as the leg 8 and is at approximate right angles thereto. This portion 34 carries the locking and switching structure, designated generally at 36 and 38 respectively.

Within the outer circular casing 26 of the steering column, which is stationary, is concentrically located a tube 40 which is the actuating tube for the steering action and within that are located further concentric tubes 42 whose function it is to carry control apparatus such as conductors for operating the horn, lights, etc. Cut longitudinally into the portion 34, and at right angles to the steering column, is a bore 44 which extends from the outer end through to the opening 24. Fitting snugly within this bore 44 is a hollow sleeve 46 which carries within it a plunger 48, which is considerably shorter than the sleeve. This plunger has at its inner end a nose 50 of reduced diameter. The outer casing 26 and the actuating tube 40 have aligned openings 52 and 54 cut therein through which the nose 50 is adapted to project and when in its innermost position will tend to prevent the tube 40 from turning.

The outer end of the sleeve has an inturned flange 56 and a coil spring 58 bears against the inner surface of this flange and against the outer face of the plunger 48 tending to keep the plunger in its innermost locking position. The central portion of the outer end of the plunger is bored out to form an opening 60 in which is supported a horizontal contact rod 62 embedded in an insulating block 64 and fitting within the opening 60, which may be composed of hard rubber or other similar material. The rod 62 has a series of peripheral grooves 66 into which the rubber flows upon molding and which prevents it from being withdrawn from the hard rubber block 64. The outer end of the rod projects through the opening in the flange 56 and carries thereon two circular disks 68 and 70 of substantially larger diameter than the opening. A ring washer 72, fitting in a groove adjacent the outer end of the rod, prevents these disks from sliding off the rod. The inner disk 68 is formed of an insulating material, 45 and the outer disk 70 is of a conducting or metallic material. A coil spring 74 surrounds the rod and presses against the insulating block 64 on its inner end and against the inner surface of the disk 68 tending to keep the two separated 50 and the disk 70 in contact with the locking ring washer 72. The purpose of the insulated disk 68 is to prevent contact between the conductor disk 72 and the metallic sleeve 46, the rod being insulated from the plunger by the insulating block 64. 55

Adjacent the outer end of the leg 34, and at right angles to the bore 44, is a second bore 76 in which is supported a substantially cylindrical body 78 of insulating material. This body has 5 cut into the inner side thereof an opening 80 into which the outer end of the sleeve projects and also the disks 68 and 70. Through the body from the top to the bottom and in alignment with its longitudinal axis, is secured a conductor rod 10 82 the two ends of which are enlarged to form electrical contacts 84 and 86. The contact 86 is drilled and tapped out to provide for a tap bolt 88 which secures one end of the electrical conductor 90 thereto. Parallel with the rod 82 are 15 two short portions 92 and 94 of a similar conducting rod which is not continuous from the upper end of the insulating block to the lower but has a gap in the center between the two. As before, an enlarged contact is formed upon 20 the outer ends of each of these portions. The two lower contacts 86 are connected to a conventional ignition circuit, which is diagrammatically shown, and comprises a battery 87, a circuit breaker 89 and a primary coil 91. Adjacent the 25 gap, between the internal ends of the portion 92 and 94, is cut a further opening 96 in the insulating body which allows the end of the rod 62 to enter when the plunger is moved to the right to bring the conducting plate 78 into contact with 30 the portions 92 and 94 to bridge the gap therebetween. The top of the insulating section 78 is slightly below the upper surface of 34, the latter projecting to a slight extent over the upper edge of the same and clamping therebetween, the angular edge of a protecting metallic cylinder 100, the latter being again offset inwardly to rotatably 35 clamp the lower annular edge 101 of a control button 102 which is formed also of insulating material, and the upper extremity 104 of which has a rectangular outline to form a gripping portion which may be easily turned by hand.

Extending vertically in the center of this switch body 102 are two aligned bores, the upper being of smaller diameter than the lower. The upper bore seats one end of a rod 106 embedded therein which projects slightly below the lower face of the member 102 and supports thereon a circular disk contact plate 108, the end of the rod being riveted over to keep the plate from disengagement but allow some axial movement. Concentric with, and surrounding a portion of the rod from the plate to the base of the larger diameter opening 110, is a circular coil spring 112 which tends to keep the plate in its lowermost position against the riveted head. The construction of the plate, which is best shown in Fig. 5, is substantially that of a disk, having extending radially from the periphery adjacent one side, two short knobs 114 which are spaced a short distance apart and are adapted to lie on opposite sides of a downwardly extending lug 116 from the member 102. The purpose of this structure is to prevent the disk 108 from having relative rotational movement with respect to the member 102. The surface of the plate 108 also has two downwardly pressed out semi-spherical portions 118 which are spaced on opposite sides of the center on the same diameter and which act as contact points. When in assembled position 60 the spring 112 presses the plate down and the portions 118 into engagement with the upper surface of the member 78 and the contacts 84.

It will thus be seen that as the upper portion 104 is turned within the cylindrical casing 100 75 that it will carry with it the lower contact plate

108 and move the portions 118 to and from bridging contact between the two contacts 84, depending upon its position thereover. The outer surface of the member 34 has marked thereon certain indicia indicating whether the switch is on or off, depending on the position of the rectangular upper member 104.

Extending parallel with the major axis of the switching means and in the body of the member 34 between the switching means and the steering 10 column, is a further bore 120 within which is supported a barrel lock having an outer sleeve 122 which fits snugly therein and also projects for a short distance through an opening in the sleeve 48 to prevent axial movement of the same. 15 A small opening 124 is drilled through the horizontal side of the member 34 and into the outer shell 122 and a pin 126 is press fitted into this opening to prevent the outer barrel from turning. The inner barrel of the lock 123 carries at 20 its lower extremity an eccentric pin 130 which projects through the opening in the sleeve 46 and operates in an elongated slot 132 in the upper surface of the plunger 48. The position of this pin is controlled by key 134 in the conventional manner.

The operation of my device is as follows:

With the locking pin 130 in the position shown in full lines in Fig. 3, the spring 58 is permitted to press the plunger 48 to its extreme left position 30 so that the nose 59 thereof engages in the opening 54 in the actuating tube 40 and prevents the same from turning which of course locks the steering wheel. At the same time this position of the plunger 48 causes the disks 68 and 70 to 35 be pulled back tightly against the flange 56 of the sleeve and out of bridging contact across the portions 92 and 94 to thereby open the ignition circuit at this point. If the member 104 is turned to its off position, the ignition circuit will be 40 further broken across contacts 84. If now the key 134 is actuated to move the locking pin 130 to the dotted line position shown in Fig. 3, this pin acting against the shoulder of the elongated groove 132 will pull the plunger 48 toward the 45 right which action causes the nose to be withdrawn from the opening 54 and allows the steering column to be rotated. This action also compresses the spring 58 and moves the contact disk 78 to the right until the same bridges the gap between the portions 92 and 94 to complete the 50 circuit thereacross. The ignition switch 38 may now be operated to directly control the ignition circuit in its on-and-off positions. Immediately, however, when the key 134 is again turned to locking 55 position, the ignition will be broken across contacts 92 and 94 to prevent continued operation of the ignition circuit when the nose 59 locks the steering column in its rotation. It should be noted that both the disks 78 and 108 are spring 60 pressed against their respective contacts in circuit closing position to insure satisfactory electrical connection. It will thus be evident that as long as the steering column cannot be turned, it will be impossible to either start or maintain the motor running which feature is necessary since it would not be possible to steer the car and an accident might result if the motor was allowed to run.

It will be seen that I have provided a simple 70 compact locking device controlling two necessary operating functions of the automobile in such manner that they are interdependent and the operation is sequential.

While I have shown and disclosed a definite 75

mechanical means for carrying out my invention, it is apparent that there may be other ways of accomplishing the same result and therefore I do not wish my invention to be limited to the 5 device as disclosed, but only by the appended claims.

I claim:

1. In control apparatus for automotive vehicles adapted to be secured to a steering column, 10 a unitary body having a longitudinal and a plurality of transverse passages therein, telescoping longitudinally movable means in the longitudinal passage, a locking bolt on one end thereof and a contact on the opposite end, locking means in one of the transverse passages engaging the movable means to shift the latter, an insulating block in the second transverse passage, a plurality of contacts in said block, a part of which are located adjacent the contact on 15 the end of the movable means and rotatable means mounted on the body adjacent the remainder of the contacts.

2. In control apparatus for automotive vehicles and adapted to be secured to the steering 20 column, a body, a telescoping member longitudinally movable within the body, one end of which projects therefrom to lock the steering column against rotation, a block of insulating material carried by the opposite end of said member, a 25 rod carried within the insulating material and two disks slidable upon the rod, one an insulating and the other conducting, resilient means on the rod bearing against the disks and a stop to maintain the disks on the rod.

3. In apparatus of the class described, a unitary body adapted to be secured to a steering column and having a longitudinal passage and a plurality of transverse passages therein, telescoping longitudinal movable means within the 30 longitudinal passage, a locking bolt on one end thereof and a contact carried on the other end thereof, means in one of said transverse passages engaging the movable means to shift the same, an insulating block in the second of said 35 transverse passages and a plurality of contacts in said block located adjacent the contact on the end of the movable means.

4. In apparatus of the class described, a body having a longitudinal passage and a plurality of 40 transverse passages therein, a plunger within said longitudinal passage having a locking means at one end thereof, a contact rod carrying a contact at one end thereof and supported by said plunger at the end opposite said locking means, 45 an insulating block in one of said transverse passages, a plurality of contacts in said block, spring means which tends to force the plunger and locking means to locking position and the plunger supported contact spaced from the contacts in said insulating block and means within the second of said transverse passages to move the plunger, locking means and contact against the force of said spring means in order to move the locking means to unlocking position and the 50 movable contact into engagement with the contacts in said insulated block.

5. In apparatus of the class described compris-

ing a unitary body adapted to be secured to a steering column and having a longitudinal passage and a plurality of transverse passages intersecting said longitudinal passage, in one of which transverse passages is a block of insulating material having a pair of spaced contacts, the combination which includes a sleeved member in said longitudinal passage having an inwardly extending flange at an end thereof adjacent the spaced contacts, a plunger within said sleeve having a locking bolt portion at one end thereof, a contact rod carried by said plunger having one end thereof fixed to said plunger for movement therewith and insulated therefrom, the other end of said contact rod extending through said flanged- 15 end of the sleeve, a contact carried by said contact rod on the end extending through said flanged-end of the sleeve, an insulating member between said contact and said sleeve, spring means within said sleeve biasing said plunger 20 away from said flange and a smaller spring biasing said contact and insulating member away from said flanged sleeve end.

6. In a device of the class described, a plunger having a locking bolt at one end thereof, a contact rod carried by the other end of said plunger and insulated therefrom, a contact disc carried by said contact rod at the end thereof opposite the locking bolt, a disc of insulating material also carried by said contact rod, means tending to 30 force the plunger, contact rod, contact disc and insulating disc in one direction and means tending to force the contact disc and disc of insulating material in the opposite direction.

7. In apparatus of the class described, a unitary body adapted to be secured to a steering column and having a longitudinal passage and two transverse passages therein, a sleeved member in said longitudinal passage having an inwardly flanged end, a plunger within said sleeved member having a locking bolt at one end, a contact rod carried by said plunger having one end thereof fixed to said plunger so that there is no relative movement therebetween and insulated from the plunger, the other end of said contact 40 rod extending through the flanged end of the sleeve, a contact carried by said contact rod on the end extending through said flanged end of the sleeve, an insulating member between said contact and said flanged end of the sleeve, spring 45 means within said sleeve biasing said plunger away from said flange, a smaller spring biasing said contact and insulating member away from said flanged sleeve end, means in one of the transverse passages for moving the plunger and parts carried thereby, an insulating block in the second passage, a pair of spaced contacts on said block adjacent the contact carried by said contact rod whereby the movable contact in one position may bridge the spaced contacts to complete an electrical circuit therethrough, a second pair of spaced contacts carried by said block of insulating material and rotatable bridging contacts supported on the body to complete an electrical circuit. 55

WILLIAM C. EDWARDS.
